UNITED STATES PATENT OFFICE.

WILLIAM BARTHOLOMEW, OF CHICAGO, ILLINOIS, ASSIGNOR TO TROY LAUNDRY MACHINERY COMPANY, LIMITED, OF CHICAGO, ILLINOIS, A CORPORATION OF NEW YORK.

WASHING-CYLINDER.

1,108,671.

Specification of Letters Patent. Patented Aug. 25, 1914.

Application filed July 11, 1910. Serial No. 571,464.

To all whom it may concern:

Be it known that I, WILLIAM BARTHOLOMEW, a citizen of the United States, residing at Chicago, county of Cook, State of Illinois, have invented certain new and useful Improvements in Washing-Cylinders, of which the following is a specification, reference being had therein to the accompanying drawing.

10 This invention relates to a washing machine and particularly to a construction wherein the parts are readily removable for renewal.

The invention has for an object to provide 15 a novel and improved construction of head having means for the removable attachment of staves thereto and the seating of ribs therein, together with means for placing a binding hoop under tension and rendering 20 its removal easily effected.

Other and further objects and advantages of the invention will be hereinafter set forth and the novel features thereof defined by the appended claims.

25 In the drawing—Figure 1 is a perspective showing the invention; Fig. 2 is a detail central vertical section; Fig. 3 is a central cross section through the cylinder of Fig. 1 looking toward the head plate; and Fig. 4 30 is a detail section on line 4—4 of Fig. 2.

Like numerals of reference refer to like parts in the several figures of the drawing.

The head comprises a hub portion 10 which is recessed to receive the trunnion 35 plate 11 carrying the bearing trunnion 12. This plate is removably secured by means of bolts 13 entering the hub portion 10. Radiating from this portion is a series of 40 spokes or arms 14 which carry at their outer ends the curved rim 15. This rim is provided with a series of rib sockets 16 disposed in alinement with the spokes 14 and adapted to receive the ribs 17 which extend into the interior of the cylinder as shown in Fig.

45 3. These ribs are secured in position by means of bolts 18 extending therethrough and also through the ends of the spokes in order to connect the rim to the spokes and also retain the rib in its socket. The staves 50 19 are secured to the rim by means of bolts 20 extending therethrough so that they may be removed whenever necessary or desired for renewal. The rim is formed with a tension portion 21 at the door 22 of the cylinder and this portion is provided with an

inset 23 from which a tightening bolt 24 extends to the binding hoop 25 which surrounds the outer face of all of the ribs and staves. By tightening the bolt 24, the hoop is drawn into the recessed portion and properly bound against the ribs and staves, while the loosening of this bolt relieves the tension and permits its removal.

At the inner face of the head, a head plate 26 is disposed which forms a closure at each 60 end of the cylinder and is provided at its periphery with a series of recesses 27 adapted to receive the inwardly projecting portion 28 of the ribs 17. These ribs are each provided at their ends with a seat 29 which

partially embraces the socket 16 of the rim and at the inner end of this seat, a kerf 30 is formed into which a portion of the head plate extends. This plate is also formed with a lateral flange 31 to form a close joint 75

with the curved edge of the rim. The segmental edges 32 of the head plate are adapted to seat in kerfs 33 formed in the staves 19 as shown by dotted lines in Fig. 3. By 80 this construction, the heads are provided with recesses by which the ribs are firmly retained in position and removably connected thereto and the spokes being disposed in alinement with the rib sockets firmly brace all of the parts. Both the staves and 85

trunnions are removably secured to the head so as to be readily renewable, while the binding hoop is adapted to be tightened by the screw carried by the head, thereby providing means for tightening or loosening 90 the hoop when desired. The connection of the head plate with the staves and ribs forms a tight joint and retains this plate in position. The invention therefore presents a simple, efficient and economically 95 constructed form of renewable cylinder in which the parts can be readily replaced when necessary from wear or other causes and can also be assembled by an ordinary workman.

Having described my invention and set forth its merits, what I claim and desire to secure by Letters Patent is—

1. In a washing cylinder, a head comprising a hub having radiating spokes, a rim having inwardly projecting rib sockets arranged on the ends of said spokes, ribs seated in said sockets and secured therein by bolts passing radially through said rim, ribs and spokes, and staves arranged on said rim between said ribs.

2. A washing cylinder, comprising head members, ribs mounted upon said head members, said ribs being provided with kerfs upon their lower ends and sides, 5 staves arranged on said head members between said ribs provided with kerfs, metal head plates having their peripheral edges arranged within the kerfs of said staves, said head plates being provided with notches 10 embracing said ribs and extending into the kerfs thereof, and hoops surrounding said ribs and staves.

3. In a washing cylinder, a head comprising a hub having radiating channel spokes, 15 a rim provided with peripheral rib sockets detachably mounted on the ends of said spokes, ribs seated in said sockets and secured therein by bolts extending radially through said ribs, rib sockets and spokes, 20 staves secured to said rim, and a hoop surrounding said staves.

4. A washing cylinder comprising a head having a rim, ribs and staves arranged on said rim provided with transverse recesses 25 on their inner faces, a head plate arranged against the inner face of said head having notches to receive said ribs, the peripheral edge of said plate being disposed within the recesses of said ribs and staves, and means 30 for holding said ribs and staves in position on said rim.

5. In a washing cylinder, a head provided with a rim having rib sockets therein, a rib provided with a recessed seat to enter said

socket and a kerf at the inner end of said 35 seat, an attaching bolt extending through said rib and rim and secured to said head, a head plate at the inner face of said head and entering said kerf, and staves carried by said rim and provided with kerfs to receive the periphery of said head plate.

6. A washing cylinder having a sectional head comprising a hub portion and a rim portion, said hub portion being provided with hollow spokes having closed outer 45 ends, said rim being provided with inwardly projecting sockets fitting on the closed ends of said spokes, said rim and spokes being secured together by radially extending bolts.

7. A washing cylinder, comprising a pair of heads, each head having a rim provided with an enlarged portion, said rim having rib sockets formed therein, ribs seated in said sockets having a greater thickness than 55 the depth of said sockets, staves arranged on said rim to each side of said ribs of the same thickness as the enlarged portion, bolts extending radially through said ribs, and binding hoops arranged over said 60 staves, ribs and enlarged portions of said rims.

In testimony whereof I affix my signature in presence of two witnesses.

WILLIAM BARTHOLOMEW.
